CLAIM

The ornamental designs for the light emitting diode (LED), as shown and described.

DESCRIPTION

FIG. 1 is a perspective view of a first embodiment of a light emitting diode (LED) showing our new design.

FIG. 2 is a front elevational view thereof, wherein a rear elevational view (not shown) is the same as with the front elevational view.

FIG. 3 is a left side elevational view thereof.

FIG. 4 is a right side elevational view thereof.

FIG. 5 is a top plan view thereof.

FIG. 6 is a bottom plan view thereof.

FIG. 7 is a cross-sectional view that cuts along the line VII—VII of FIG. 5.

FIG. 8 is a perspective view of a second embodiment of a light emitting diode (LED).

FIG. 9 is a front elevational view of the embodiment of FIG. 8, wherein a rear elevational view (not shown) is the same as with the front elevational view.

FIG. 10 is a left side elevational view of the embodiment of FIG. 8.

FIG. 11 is a right side elevational view of the embodiment of FIG. 8.

FIG. 12 is a top plan view of the embodiment of FIG. 8.

FIG. 13 is a bottom plan view of the embodiment of FIG. 8; and,

FIG. 14 is a cross-sectional view that cuts along the line XIV—XIV of FIG. 12.
